US0D1027947S

(12) **United States Design Patent** (10) Patent No.: **US D1,027,947 S**
(45) Date of Patent: ** May 21, 2024

(54) **PASSWORD MANAGEMENT DEVICE**

(71) Applicant: **Peter Thomas**, Cardiff (GB)

(72) Inventor: **Peter Thomas**, Cardiff (GB)

(**) Term: **15 Years**

(21) Appl. No.: **35/513,909**

(22) Filed: **Sep. 30, 2021**

(80) **Hague Agreement Data**

Int. Filing Date: **Sep. 30, 2021**

Int. Reg. No.: **DM/216660**

Int. Reg. Date: **Sep. 30, 2021**

Int. Reg. Pub. Date: **Apr. 1, 2022**

(30) **Foreign Application Priority Data**

Apr. 1, 2021 (GB) 6127965

Apr. 1, 2021 (GB) 6127966

Apr. 1, 2021 (GB) 6127967

CLAIM

The ornamental design for the password management devices, as shown and described.

DESCRIPTION

1. Password management device

1.1 : Perspective top view

1.2 : Top

1.3 : Bottom

1.4 : Front

1.5 : Back

1.6 : Left

1.7 : Right

1.8 : Perspective bottom view

1 Claim, 8 Drawing Sheets
